Specification of Letters Patent. Patented Apr. 20, 1915.

Original application filed May 4, 1909. Serial No. 493,922. Divided and this application filed February 27, 1912. Serial No. 680,145.

To all whom it may concern:

Be it known that I, ELLIS T. SILVIUS, a citizen of the United States, residing at Indianapolis, in the county of Marion and 5 State of Indiana, have invented a new and useful Filing Appliance, of which the following is a specification, reference being had to the accompanying drawings, and to the letters and figures of reference marked 10 thereon.

This invention relates to apparatus for filing papers of various kinds, the apparatus being variously known as credit accounting registers, filing appliances, or credit cabinets, and by various other names.

The invention has reference more particularly to appliances for systematically filing bill-slips used in credit account systems, or other papers, a filing appliance of the above-mentioned character showing the present invention having been described in my pending application for Letters Patent filed May 4, 1909, Serial Number 493,922, of which this is a divisional application for Letters 25 Patent.

One object of the present invention is to provide improved means for removably supporting and retaining a group of holders or leaves in a casing or frame, so as to constitute a filing cabinet, and for supporting the group of leaves in upright position and in a rectangular pack when removed from the casing or frame.

A further object is to provide holders, 35 leaves or frames with an improved base or retaining plate that shall be so constructed and permanently connected to the leaves as to be capable not only of retaining the leaves in the casing or frame, but to substantially 40 support the leaves when removed from the casing or frame and permit the group of leaves to slide freely into or out of a fire proof safe or vault where the leaves may be kept to guard the contents when the filing 45 appliance is not in use.

A still further object of the invention is to provide an improved casing or frame adapted to removably hold the base or retaining plate therein.

With the above-mentioned and other objects in view, the invention comprises novel features of construction in the casing or frame constituting a part of the filing case

net and a series of leaves or frames hinged together and provided with devices for retaining papers thereon, one of the leaves or frames having a base or retaining plate hinged thereto, and means for locking the base or retaining plate to the casing.

The invention consists further in the novel parts, and combinations and arrangements of parts, as hereinafter particularly described and pointed out in the appended claims.

Referring to the drawings, Figure 1 is a 65 vertical longitudinal section of a casing or frame and a series of leaves or frames mounted therein, as at the left hand side of the leaves, the latter being in prone position, the lower portion of the casing being broken 70 away; Fig. 2, a rear perspective view of the leaf follower constituting a device for maintaining the upright leaves in substantially upright position; Fig. 3, a fragmentary side elevation of a group of leaves removed from 75 the casing and supported uprightly on the base or retaining plate; Fig. 4, a fragmentary vertical central section of the filing cabinet with the leaves in normal position, and supported and held in the casing or frame 80 by means of the base or retaining plate; Fig. 5, a fragmentary perspective view of two leaves connected together by a butt or hinge of common construction which is preferably employed, for connecting the leaves together 85 in a group so as to swing pivotally each relatively to the others; Fig. 6, a fragmentary central sectional view of the casing or frame looking in the direction opposite to Fig. 4; Fig. 7, a perspective view of one of 90 the guides for the follower; Fig. 8, a fragmentary perspective view of the series of leaves and the base or retaining plate removed from the casing or frame; Fig. 9, a fragmentary perspective view of the casing 95 or frame as preferably constructed for securing the base or retaining plate therein; and Fig. 10, a fragmentary detail of parts of the appliance for locking the leaves to the supporting base or plate.

In the different figures of the drawings similar reference characters indicate like parts or features of construction herein referred to.

The casing or frame for the series of 105 leaves may be variously constructed. As

shown, it comprises a desk part consisting of a bottom 1, sides 2 and 3 secured to the bottom, the rear portion of the desk part having an upright casing suitably erected thereon and preferably comprising two sides 4 and 5 continuing upward from the sides 2 and 3, respectively, and a back 6 joined to the sides and extending down to the bottom 1 to form the back of the desk part, a rail 7 being suitably secured at a suitable distance above the bottom 1 and extending between the sides 2 and 3 at the lower, forward portions of the upright sides 4 and 5, and a floor or shelf 8 being suitably supported and extending from the rail 7 rearward to the back 6. The rearward portion of the upper side of the rail is preferably recessed to receive the floor or shelf and leave a rearwardly facing shoulder 9 extending above the plane of the top of the floor or shelf. Preferably the shelf has a forwardly facing shoulder 10 on the rearward upper portion thereof. A door 11 may be connected by hinges 12 to the forward side 25 of the rail 7. The door normally lies on the sides 2 and 3 to form a top for the desk part and may be moved to an upright position against the fronts of the sides 4 and 5 to inclose the leaves when desired. The desk part, however, may be variously constructed, various details thereof being unrelated to the present improvement. The casing may also be provided with a cover or lid 13 which, when provided, is connected by 30 hinges 14 to the back 6, the under side of the cover being provided with a suitable catch 15 adapted to engage a projection 16 on the inner side of the side 5 of the casing to hold the cover in closed position, a suitable lock 17 being provided for locking the door 11 to the cover 13. The cover is provided with a suitable prop 18 that is adapted to engage a supporting device 19 secured to the side 5 for holding up the cover when 35 the filing appliance is in use, as in Fig. 1.

A suitable base or retaining plate 20 is provided for supporting and holding the leaves in the casing or frame and is removably mounted upon the floor or shelf 8 between the shoulders 9 and 10 which serve as guides and may be secured against movement by various means, preferably by fingers or bars 21, 21', mounted on the rearward portion of the floor or shelf 8 and 50 extending forwardly beyond the shoulder 10 and over the rearward end of the base or retaining plate 20 when the latter is in position in the casing or frame. Preferably the base or plate 20 is further held on the floor or shelf by means of a suitable button or fastening catch 22 connected to the shelf 8 or rail 7 by means of a pivot 23 and movable into contact with or on top of the base or retaining plate at its forward edge. It 55 should be understood that the shoulders 9

and 10 constitute spaced bars between which the base or plate 20 is retained in fixed relation to the casing or frame and prevented from shifting either forwardly or rearwardly, it being evident that the shoulders or their equivalent may be variously formed otherwise than as described. A pair of pivoting stands or ears 24 and 25 are formed or secured on the top of the forward portion of the base or retaining plate 20 for pivotally supporting the foremost one of the series of leaves, there being a suitable number of leaves or frames, 26 indicating the foremost one, 27 the intermediate leaves, and 28 the rearmost one of the leaves, each one of the series of leaves having a hinged bar or base bar 29 which is the bottom portion of the leaf or frame when in its normal upright position. The lower forward edge portion of the foremost leaf 26 is connected by means of pivots or hinge-pins 30 and 31 to the pivoting stands or ears 24 and 25, these pivots or hinge-pins being connected directly with the hinge-bar of the leaf. The series of leaves or frames are suitably connected together preferably by means of butts or hinges 32, 32', each of which as is well known comprises hinge-plates and a hinge-pin 33 connecting the two plates together, and in adapting the butts for the purpose they are secured to the under sides of the hinge-bars 29, preferably by means of screws in a well known manner so as to be readily detached if desired, and so that additional leaves may be conveniently connected with the series if found desirable. It will be understood that the hinge-pins 33 are arranged on the planes of the adjacent meeting sides of the leaves or frames. All the frames or leaves, as will be seen, are pivotally supported by means of the pivots or hinge-pins 30 and 31, and when in upright position may be supported squarely upon the base or retaining plate 20, the rear portion of the latter preferably having cushions or buffers 34, 34', thereon directly supporting the rearmost one of the leaves and not permitting the hinges to noisily come in contact with the base, the latter preferably being composed of metal. It will therefore be seen that the foremost one and the rearmost one of the leaves may be supported substantially by the base and they in turn support the intermediate leaves by means of their hinges. The base or retaining plate is 11 preferably of a width equal to the depth of the group of leaves when in upright position.

For the purpose of securely holding the base or retaining plate 20 to the leaves when all are removed from the casing or frame for convenient handling, a locking-bar 35 is provided that has a journal 36 extending laterally on one end thereof which is mounted rotatively in a suitable journal-box 37 that 120

is mounted on the base 20, the locking-bar having a finger 38 thereon which is adapted to engage a latch plate 39 secured on the under side of the hinge-bar 29 of the rearmost leaf or frame, the locking-bar 35 lying on the base 20 when not in use, and when swung upward pivotally it engages the rear side of the rearmost leaf to prevent rearward movement of the leaf relatively to the base or the adjacent leaf, while the finger 38 prevents the base from moving away from the leaves, so that when removed from the casing the series of leaves will stand upright as a rectangular pack as shown in Fig. 3, in which condition the pack may be readily handled and inserted into a receptacle for safe keeping. The leaves or frames, as will be understood, are provided with suitable spring clamps 40 or other devices for holding papers on the fronts and backs of the leaves.

In order to guide the rearmost leaf in its up and down movements and prevent it from swinging rearward, the rearmost leaf 25 stands against a device which is preferably movable therewith, and in order to support the device or follower two grooved guide-bars 41 and 42 are secured to the inner sides of the casing sides 4 and 5, respectively, and 30 preferably extend approximately from the back 6 upward toward the forward edges of the sides of the casing. The follower preferably comprises a carriage having two sides 43 and 44 and a cross-bar 45 connected to the 35 two sides, the sides having vertical guide grooves 46 and 47 in the inner sides thereof respectively. The carriage is provided with rollers 48 and 48' to operate in the guide-bar 41 and other rollers 49 and 49' to operate 40 in the guide-bar 42, and the sides of the carriage have arms 50 and 50' thereon respectively that extend upward and are provided at their upper ends with rollers 51 and 51', respectively, against which the rearmost leaf 45 has contact. The side edges of the rearmost leaf 28 has projecting pins 52 that extend into the guide grooves that are formed vertically in the carriage, so that vertical movement may occur as between the rearmost leaf and the carriage of the follower during irregular or variable movement of the rearmost leaf as it describes arcs of circles either about the axis of the pivots of the foremost leaf or the pivots of the other 55 leaves, the rearmost leaf therefore controlling the movement of the follower.

When it is desired to assist the operator in moving the leaves to upright position, a coil-spring 53 is connected to the cross-bar 50 or otherwise to the carriage, and is connected also to a projection 54 on the side of the rearmost leaf 28, the spring being so strained as to exert its force to draw the rear leaf to an upright position and hold it 65 against the arms of the follower, and by

means of the hinging connections assisting to draw up the remaining leaves, the spring permitting the leaves to be moved down to prone position.

In practical use, the front of the casing or frame is opened and the operator selects one of the leaves or frames to which he desires to gain access and draws it and also any leaves that may be forward of it to prone position, the remaining leaves being moved forward and upward in upright position, the follower also being moved forward and upward by the rearmost leaf. Having accomplished the purpose of manipulating the leaf or leaves the operator lifts the forward leaf or leaves from prone to upright position, the series of leaves settling rearwardly and downwardly by force of gravity to their upright position on the base or retaining plate 20. When it is desired to remove the leaves from the casing or frame the button 22, or such securing device as may have been provided, is swung on its pivot to release the base or plate 20 and the latter is lifted slightly at its forward end and then slightly moved forward so as to be released from the devices 21, 21', and after disconnecting the rearmost leaf from the follower the leaves and the base or plate 20 are removed together from the casing, and then the leaves are locked against pivotal movement in upright position against the base or plate by means of the locking devices provided therefor as hereinbefore described.

Other results and advantages of the improvement in operation will be readily understood from the foregoing description of the construction and function of the various parts thereof.

Having thus described the invention, what is claimed as new is—

1. In a filing appliance of the class described, the combination of a plurality of leaves, connections between the lower ends of the leaves permitting pivotal movements of the leaves relatively to each other and operating when one or more of the leaves are reclined to move the lower ends of the remaining leaves forwardly, said leaves being arrangable in a rectangular pack and portable for storage, a support or shelf for supporting said leaves for normal operation, a retaining member hinged to one end leaf and detachably connected with the other end leaf, and means for detachably securing said retaining member to said support.

2. In a filing appliance, the combination of a plurality of leaves, connections between the lower ends of the leaves permitting pivotal movements of the leaves relative to each other and operating when one or more of the leaves are reclined to move the lower ends of the remaining upright leaves for

- wardly, a retaining base-plate hinged at one of its ends to the foremost one of the leaves, and means for detachably securing the rearmost one of the leaves to the opposite end of said base-plate.
3. In a filing appliance, a floor or shelf provided with two oppositely arranged guides on the top thereof, a base or retaining plate removably mounted on the floor or shelf between the guides and positioned thereby, and a plurality of leaves hinged together, one of the leaves being hinged to the base or retaining plate.
4. In a credit cabinet of the class described, a casing or frame provided with a shelf, a series of leaves provided with base bars, hinge plates secured to said bars and pivotally connected together between the meeting faces of the bars, and a retaining plate hinged to the base bar of the front leaf and removably secured to the shelf.
5. In a filing appliance, the combination of a series of pivotally mounted bill holding leaves, a base relative to which the leaves are adapted to swing from a substantially vertical to a substantially horizontal position, one of the end leaves of the series having a latch-plate, and a locking bar pivotally mounted on the base and provided with a latch for engaging with the said latch-plate.
6. In a filing appliance, the combination of a series of pivotally mounted bill holding leaves, a base relative to which the leaves are adapted to swing from a substantially vertical to a substantially horizontal position, one of the end leaves of the series having a latch-plate, and a locking bar pivotally mounted on the base on an axis at right angles to the axis of the leaves and provided with a latch for engaging with the said latch-plate.
7. A case, a base secured removably in the case, a plurality of normally upright leaves connected one to another rotatably and the foremost one of the leaves pivotally supported on the base and supporting the remaining leaves, the rearmost one of the leaves having a latch-plate on the under side thereof and a locking bar mounted on the base rotatably to be moved against the back of the rearmost leaf and having a finger thereon to engage the latch-plate.
8. A filing appliance including a plurality of leaves, hinges connecting the leaves together, a base or retaining plate hinged at one end to the foremost one of the leaves, and means for detachably securing the rearmost one of the leaves to the opposite end of the base or retaining plate, the said means including a member arranged perpendicular to the base when in operative position and serving as a back for the leaves to retain them in a rectangular pack.
9. In a filing appliance, the combination of a support provided with a shelf, a series of leaves arranged to be assembled face to face, pivotal connections between the leaves permitting them to swing relatively to each other, a base or retaining plate to which one end leaf of the series is pivotally connected, and means for detachably securing said base or retaining plate on the floor, the said means including a member mounted to swing on a vertical axis.
10. In a filing appliance, the combination of a plurality of leaves, connections between the lower ends of the leaves permitting pivotal movements of the leaves relatively to each other and operating when one or more of the leaves are reclined to move the lower ends of the remaining upright leaves forwardly, said leaves being arrangeable in a rectangular pack and portable for storage, a support or shelf for supporting said leaves for normal operation, a retaining member hinged to one end leaf and detachably connected with the other end leaf, and means for detachably securing said retaining member to said support and against movement relative thereto during the normal operation of the appliance.
11. In a filing appliance, the combination of a base or retaining plate, a bar having a journal that is rotatively mounted on one end of the base or plate, the bar being movable to upright position, and a plurality of leaves hinged together, the foremost one of the leaves being hinged to the opposite end of the base or plate, the leaves being supported uprightly on the base or plate with the rearmost leaf in contact with the upright bar.
12. In a credit cabinet of the class described, a casing or frame provided with a shelf, a series of leaves, connections between the lower ends of said leaves permitting said leaves to swing relatively to each other and operating to move the lower ends of the remaining upright leaves forwardly as one or more of them are reclined, a retaining member hinged to the lower end of the front leaf and detachably connected to the lower end of the rear leaf of said series, and means for removably securing said retaining member to the casing or frame during the normal operation of the appliance.

In testimony whereof, I affix my signature in presence of two witnesses.

ELLIS T. SILVIUS.
